(57) **CLAIM**

The ornamental design for padlock, as shown and described.

DESCRIPTION

FIG. 1 is a perspective view of a padlock showing my new design;

FIG. 2 is a front elevational view thereof; the rear elevational view being a mirror image;

FIG. 3 is a top plan view thereof;

FIG. 4 is a bottom plan view thereof;

FIG. 5 is a left side elevational view thereof; and,

FIG. 6 is a right side elevational view thereof.

The portions of the design shown in broken lines form no part of the claimed design.
